UNITED STATES PATENT OFFICE.

CHARLES M. LEVY, OF NEW YORK, N. Y.

DESIGN FOR A LOCKET CIGAR-CUTTER CASE.

41,847.

Specification for Design. Patented Oct. 17, 1911.

Application filed May 20, 1911. Serial No. 628,560. Term of patent 14 years.

To all whom it may concern:

Be it known that I, CHARLES M. LEVY, a citizen of the United States, residing in the borough of Manhattan, in the city, county, and State of New York, have invented a new, original, and ornamental Design for Locket Cigar-Cutter Cases, of which the following is a specification, reference being had to the accompanying drawing, forming a part hereof.

In the drawing, Figure 1 is a front elevation of a cigar cutter case showing my design; Fig. 2 a side elevation thereof; Fig. 3 a rear elevation; and Fig. 4 an end elevation.

I claim:

The ornamental design for a locket cigar cutter case as shown.

CHARLES M. LEVY.
